UNITED STATES PATENT OFFICE

148,076

DESIGN FOR A CARD INDEX OR THE LIKE

Isaac Keesing, Jr., Washington, D. C.

Application January 24, 1945, Serial No. 117,565

Term of patent 3½ years

(Cl. D74—2)

To all whom it may concern:

Be it known that I, Isaac Keesing, Jr., a citizen of the Netherlands, residing in Washington, District of Columbia, have invented a new, original, and ornamental Design for Card Indexes or the like, of which the following is a specification, reference being had to the accompanying drawing, forming part thereof in which:

Fig. 4 is a front view of one of the index cards shown in the other figures for the purpose of bringing out more clearly the details thereof.

I claim:

The ornamental design for a card index or the like, as shown and described.

ISAAC KEEsing, JR.
